ATT'YS.

UNITED STATES PATENT OFFICE.

OSCAR ROESEN, OF NEW YORK, N. Y., ASSIGNOR TO R. HOE AND CO., OF NEW YORK,
N. Y., A CORPORATION OF NEW YORK.

INKING MECHANISM FOR PLATE-PRINTING MACHINES.

1,253,423.

Specification of Letters Patent. Patented Jan. 15, 1918.

Application filed November 10, 1915. Serial No. 60,654.

To all whom it may concern:

Be it known that I, OSCAR ROESEN, a citizen of the United States, residing at New York city, county of Kings, and State of New York, have invented certain new and useful Improvements in Inking Mechanism for Plate-Printing Machines, fully described and represented in the following specification and the accompanying drawings, forming a part of the same.

This invention relates to certain improvements in inking devices for plate machines.

In plate printing machines, the printing is done from a flat plate or other surface by means of depressed lines. To effect printing by these plates the whole surface of the plate is first covered with ink, so that the lines are effectually filled. The surface of the plate, however, where there are no lines, must be clean, and to effect this, the plate is wiped in some manner, usually an endless roll of cloth which is gradually renewed by suitable feeding mechanism. The ink used in plate printing is expensive, and the wiping as ordinarily done wastes the surplus ink which is wiped off. Furthermore, the wiping of the surplus ink causes a more rapid deterioration of the wiper than would be the case if the surplus ink were removed prior to wiping, and as the wipers are expensive it is desirable to keep them in use as long as possible.

It is the object of this invention to provide a simple construction for use with plate printing machines in which all or the greater part of the surplus ink on the surface of the plate is removed and delivered to a receptacle so that it can be used again, thus effecting a considerable saving in ink and in the wipers.

For a full understanding of the invention reference may be had to the accompanying drawings, in which—

Figure 1 is a side elevation of so much of a plate printing machine as is necessary for an understanding of the invention, showing the device employed for removing the surplus ink, and

Fig. 2 is a plan view, partly in section, of the construction shown in Fig. 1, the figure being broken to economize space.

Referring now to these drawings, the invention is illustrated in connection with a plate printing machine employing flat plates

1 carried on a suitable bed 2 which is reciprocated in any usual or desired manner. Inking devices of the usual form, including a fountain roll 3 and a distributor roll 4 suitably mounted in a frame 5, are provided for inking the plates.

In constructions embodying the invention in its best form there will be provided ink removing devices which shall act to remove practically all the surplus ink from the surface of the plate and to deliver this ink to a receptacle so that the ink is saved and can be used over again. While these ink-removing devices may be of various configuration, as shown there is provided a doctor or scraper 6 which is in the form of a thin blade extending across the machine and mounted to bear on the plate. This doctor blade is mounted in any suitable manner, and in the particular construction illustrated a pair of brackets 8, 9 are secured to the frame 5, before referred to, and to these brackets are pivoted arms 10, 11 which are connected by a cross-bar 12 between which and a second cross-bar 13 the doctor blade is clamped. The pressure of the doctor on the plate is or may be regulated by springs (not shown) through spring rods 14 secured to the arms.

In accordance with the invention there is provided a receptacle for holding the surplus ink scraped or cleaned from the plate, and means whereby such cleaned or scraped ink is delivered by the doctor to the receptacle. While the means for effecting this may be varied, as illustrated the receptacle is in the form of a removable trough 15 removably secured to blocks 16 carried by the arms 8, 9, before referred to. This receptacle is, as illustrated, provided with a forwardly extending, downwardly inclined, flange or lip 17, which extends almost to the rear side of the doctor, so that as the doctor cleans or scrapes the ink from the plate the ink will be forced up this inclined lip into the receptacle and thus saved, to be again used.

Furthermore, in addition to saving the ink, the surplus ink is substantially removed from the plate before the plate is acted on by the wipers and but little, if any, ink is left for the wipers to remove, thus effecting a very considerable saving in the wipers.

While the invention has been shown and

described in its preferred form, it will be understood that changes and variations may be made in the construction shown and described without departing from the invention.

What is claimed is:

1. In a plate printing machine the combination with a flat engraved plate, a support therefor, means for inking the plate, 10 a pair of arms pivoted adjacent the support on each side thereof, means for adjusting the arms toward and from the support, clamping bars carried by the arms and extending across the face of the form, a 15 scraper comprising a flat blade clamped between the bars bearing on the form for removing surplus ink therefrom, a receptacle carried by the arms for such ink, and a 20 guide extending across the front of the receptacle substantially co-extensive with and

coöperating with the blade for delivering the scraped ink to the receptacle.

2. In a plate printing machine the combination with an engraved form, a support for the form, means for inking the form, a pair 25 of frames on each side of the support, holder arms pivoted in the frames, a scraper blade mounted in the arms, a removable receptacle carried in the arms and a guide carried on the front of the receptacle substantially co-extensive with and coöperating with the blade whereby the scraped ink will be delivered to the receptacle. 30

In testimony whereof, I have hereunto set my hand, in the presence of two sub- 35 scribing witnesses.

OSCAR ROESEN.

Witnesses:

RICHARD KELLY,
HAROLD M. TILLINGHAST.
